US00D963479S

(12) **United States Design Patent** (10) **Patent No.:** **US D963,479 S**
Whincup et al. (45) **Date of Patent:** **** Sep. 13, 2022**

(54) **BOTTLE**

(71) Applicant: **FORDS PACKAGING SYSTEMS LIMITED**, Bedford (GB)

(72) Inventors: **Laura Anne Whincup**, Bedford (GB); **Sefton Whitlock**, Bedford (GB)

(73) Assignee: **FORDS PACKAGING SYSTEMS LIMITED**, Bedford (GB)

(**) Term: **15 Years**

(21) Appl. No.: **29/701,060**

(22) Filed: **Aug. 8, 2019**

(51) LOC (13) Cl. **09-01**

(52) U.S. Cl.

USPC **D9/454**

(58) **Field of Classification Search**

USPC D9/500–505, 516, 519, 523, 529, 549, D9/550, 556, 558, 563, 575, 520, 547, D9/548, 452, 454, 435, 440, 445, 449, D9/447, 438, 439, 442, 443, 444, 682, D9/686, 450, 518; D32/31; D28/79, 89; D6/515; D7/507, 509–511, 523, 605, D7/608, 900

(57) **CLAIM**

The ornamental design for a bottle, as shown and described.

DESCRIPTION

FIG. 1 is a front, right-side, and top isometric view of a bottle showing the new design.

FIG. 2 is a front elevation view of the bottle.

FIG. 3 is a rear elevation view of the bottle.

FIG. 4 is a right-side elevation view of the bottle.

FIG. 5 is a left-side elevation view of the bottle.

FIG. 6 is a top plan view of the bottle.

FIG. 7 is an exploded front, right-side, and top isometric view of the bottle; and,

FIG. 8 is an exploded right-side elevation view of the bottle. The broken lines depict portions of the bottle that form no part of the claimed design.

1 Claim, 8 Drawing Sheets
